UNITED STATES PATENT OFFICE

GRANVILLE A. HUMASON, OF HOUSTON, TEXAS

PACKER

Application filed November 23, 1929. Serial No. 409,222.

This invention relates to new and useful improvements in a packer.

One object of the invention is to provide the packer of the character described adapted 5 to be set between an inner pipe and an outer pipe in a well bore to form a fluid tight joint between said pipes. The packer is primarily intended for the purpose of forming a seal between the upper end of a screen, in a well 10 bore, and the surrounding casing in said bore.

Another object of the invention is to provide, in apparatus of the character described, means for securely holding the packer set, or expanded at the desired place in the casing.

15 A still further feature of the invention resides in the provision of a packing apparatus of the character described that may be released from the surrounding casing and withdrawn or relocated in the casing if desired.

20 With the above and other objects in view, the invention has particular relation to certain novel features of construction, operation and arrangement of parts, an example of which is given in this specification and illustrated in the accompanying drawings where- 25 in:—

Figure 1 shows a side elevation partly in section of the upper end of the apparatus shown in collapsed position in the casing.

30 Figure 2 shows a similar view of the lower end of the apparatus.

Figure 3 shows a side elevation partly in section of the upper end and of the apparatus shown in expanded position in the casing.

35 Figure 4 shows a similar view of the lower end thereof, and

Figure 5 shows a cross sectional view taken on the line 5—5 of Figure 3.

In the drawings, the numeral 1 designates 40 a casing in a well bore. The numeral 2 designates a tubular packer support whose upper end is outwardly flared at 3 and threaded unto the lower end of which is a coupling 4 whose lower end is downwardly tapered 45 forming an expander 5. Around the packer support there is a sleeve like expansible packer 6 which is formed of rubber or other suitable expansible material and around which there is an envelope 7 formed of lead or other 50 soft metal. The lower end of this packer

is seated in a groove 8 in the upper end of the coupling 4 and the upper end of said packer is seated in a similar groove 9 in the lower end of the setting nipple 10. Embedded within the material of the packer 6 are the lower 55 and upper metallic reinforcing bands or rings 11, 12 and lower and upper screws 13, 14 are threaded through the corresponding upper and lower ends of the coupling 4 and setting nipple 10 said setscrews also extending 60 through said packer and the reinforcing bands 11, 12 thereof.

Threaded into the upper end of the setting nipple 10 there is an upwardly tapering expander 15, and threaded through this expander by left hand threads 16 there is a connecting nipple 17 threaded onto the upper end of which there is a coupling 18. The upper end of the coupling 18 has oppositely disposed J-slots 19, 19. There is a setting string of pipe 70 20 whose lower end fits into the upper end of the coupling 18 and is provided with oppositely disposed studs 21, 21 adapted to be engaged into and disengaged from the corresponding J-slots 19. 75

Above the coupling 15 the nipple 17 has an annular, wide, external rib 22. Above this rib around the nipple 17 are the arcuate anchors 23, provided with the peripheral grooves 24 in which is seated a retaining ring 25. These anchors rest on the rib 22 and closely surround the nipple 17 and depending from the respective anchors are the shanks 26 whose lower ends terminate in the wedge shaped slips 27 which ride on the external surface of the expander 15 and which have the external teeth 28. 80 85

The lower end of the nipple 17 has the external annular rib 29, adapted to engage the lower end of the expander 15 and below this rib and located in the setting nipple 10 there are the vertical keys 30 spaced apart there-around and which work in the external vertical keyways 31 in the upper end of the packer support 2. 90 95

Threaded into the lower end of the coupling there is a tubular section 32, and whose lower end has an external annular rib 33.

Around the tubular section 32 there is a screen support 34 having an internal annular 100

shoulder 35 which rests on the rib 33 and threaded into the lower end of said support, with its upper end abutting the rib 33 there is a coupling 36 into which the upper end 5 of the screen 37 is connected. The tubular section 32 thus has a swiveling, or rotatable, connection with the screen support but is held by the rib 33 against longitudinal movement relative to said support.

10 Around the expander 5 are the wedge shaped slips 38, which work against the expander 5 and have the external teeth 39. These slips have downwardly extended shanks 40 which surround the tubular section 15 32 and have external grooves 41 in which is located a retaining ring 42 which holds said slips 38 assembled. When the apparatus is assembled and the packer is in collapsed position the shanks 40 are connected to the section 32 by means of right hand threads 43. The shanks 40 are seated on a coil spring 44 which is housed in between said section 32 and the lower ends of said shanks and the upper end of the screen support, and is supported 20 on an internal annular shoulder 45 of said screen support. When the threads 43 are in intermeshed said spring is under compression.

25 The lower ends of the shanks 40 and the upper end of said screen support have the intermeshing fingers 46, 47, which permit the longitudinal movement of the dogs 38, relative to said screen support but which prevent their relative rotation.

30 In operation the apparatus is assembled as shown in Figures 1 and 2 and let down into the well bore until the screen 37 rests on the bottom of the bore. The string 20 is then turned to the right and the tubing 17, the setting nipple 10 and the packer support and tubular section 32 will be turned and the threads 43 being right hand threads will be disengaged and thereupon the spring 44 will operate to force the slips 38 into engagement 35 with the casing and to anchor the apparatus to the casing. The string 20 is then turned to the left and, the threads 16 being loosely connected, the nipple 17 will be screwed down through the coupling 15 until the rib 22 there-

40 of engages the upper end of the said coupling 15. The slips 27, will thus be lowered relative to the expander coupling 15 so that they will engage with the inside wall of the casing 1. The weight of the string 20 is then applied and it will force the setting nipple 10 downwardly relative to the packer support 2 and this will expand the packer 6 out against the casing as shown in Figure 3, the keys 30 and keyways 31 permitting this longitudinal movement of the setting nipple relative to the packer support. The slips 38 will sustain the weight of the load above and will relieve the screen of this load and the slips 27 will engage the casing to hold the packer 45 expanded.

The string 20 may then be suitably turned to release its studs 21 from the J-slots 19 and withdrawn leaving the packer set. If however, it be desired to withdraw the packer, or to move it upwardly and reset it the stem 70 20 may be engaged with the coupling 18 and turned to the right and this will operate, through the left hand threads 16, to elevate the nipple 17 relative to the setting nipple 10 and the rib 22 will engage the anchors 23 to 75 pull the slips 27 upwardly relative to their expanders whereupon they will contract and release the casing 1 and the apparatus may then be elevated and reset, as above explained, or withdrawn from the casing.

80 The drawings and descriptions disclose what is considered to be a preferred form of the invention by way of illustration only, while the broad principle of the invention will be defined by the appended claims.

85 What I claim is:

1. A packer including a tubular packer support, an expandable packer sleeve thereon, a tube connected to and depending from said support and including an expander, a pipe support around and having a swiveling connection with said tube, expandable casing engaging means around said expander, a yieldable seat forming a support for said engaging means, a setting nipple on said packer support abutting one end of said packer sleeve and including an expander, expandable casing engaging means around said last mentioned expander, a tubular nipple having a threaded connection with said setting nipple, said tubular nipple forming a support for said last mentioned casing engaging means, means on the tubular nipple engageable with said expander for limiting the longitudinal movement of said tubular nipple relative to said setting nipple, operative connections between said packer support and said setting nipple permitting their relative longitudinal movement but preventing their relative rotation.

100 110 115 120 125 130

2. A packer including a tubular packer support, an expandable packer sleeve thereon, a tubular screen support below the packer support, a tubular member connected to the packer support within and having a swiveling connection with the screen support and including an expander, casing engaging means around said expander, and having a releasable connection with said tubular member, a yieldable seat arranged to act against said engaging means, a setting nipple abutting the upper end of said sleeve and including an expander, expandable casing engaging means around said last mentioned expander, operative connections between the setting nipple and packer support permitting their relative lengthwise movement but preventing their relative rotation, a tubular nipple having a threaded connection with said setting nipple and forming a support

- for said last mentioned casing engaging means and means on said nipple for limiting the longitudinal movement of the tubular nipple relative to the setting nipple.
3. A packer including a tubular packing support, an expansible packing element thereon, a tubular screen support below the packer support, tubular means connected to the packer support and within and having a swiveling connection with the screen support, and including an expander, lower casing engaging means around said expander, releasable interengaging means between said tubular means and said casing engaging means, a yieldable seat operable against said casing engaging means, interengaging means between said screen support and said casing engaging means formed to permit their relative lengthwise movement and to prevent their relative rotation, a setting nipple above said packing element and having an upper expander, expansible casing engaging means around said upper expander, operative connections between the setting nipple and packer support permitting their relative lengthwise movement but preventing their relative rotation, a tubular member having a threaded connection with said setting nipple and forming a support for said last mentioned engaging means, and means engageable with said upper expander for limiting the longitudinal movement of said tubular member relative to the setting nipple.
4. A packer including a tubular packer support, an expansible packing element thereon, a tubular screen support below the packer support, tubular means connected to the packer support having a swiveling connection with the screen support and including a lower expander, casing engaging means around said expander and having a threaded connection with said tubular means, a yieldable seat operable against said engaging means, a setting nipple above said packing element and having an upper expander, expansible casing and engaging means around said upper expander, a tubular member having a threaded connection with said setting nipple, interengaging means between said tubular member and said last mentioned casing engaging means through which the latter may be actuated by the former out of casing engaging position, means on the tubular member and engageable with the upper expander for limiting the longitudinal movement of said tubular member relative to said setting nipple.
5. A packer including a tubular packer support, an expansible packing element thereon, a tubular screen support below the packer support, tubular means connected to the packer support and having a swiveling connection with the screen support and including a lower expander, casing engaging means around said expander and having a releasable threaded connection with said tu-
- bular means, a yieldable seat forming a support for said engaging means when the latter are released from said tubular means, a setting nipple above said packing element and having an upper expander, expansible 70 casing engaging means around said upper expander, a tubular member having a threaded connection with said setting nipple, interengaging means between said tubular member and said last mentioned casing en- 75 gaging means through which the latter may be actuated by the former out of casing en- gaging position, means on the tubular mem- ber for limiting the longitudinal movement of said tubular member relative to said set- 80 ting nipple, and interengaging means be- tween the setting nipple and packer support permitting their relative longitudinal move- ment but preventing their relative rotation.
6. A packer including a packer support, 85 an expansible packing element thereon, a screen support below the packer support, means connected to the packer support hav- ing a swiveling connection with the screen support and including a downwardly taper- 90 ing lower expander, casing engaging means about said expander and having a releasable threaded connection with said means connected to said support, a yieldable seat form- 95 ing a support for said engaging means when the latter is released from said connection, a setting nipple above said packing element and having an upwardly tapering upper ex- 100 pander, casing engaging means about said upper expander, means having threaded con- 105 nection with said setting nipple and also having means engageable with said last mentioned casing engaging means through which the latter may be actuated by the former out of casing engaging position.
7. A packer including a packer support, 110 an expansible packing element thereon, a pipe support below the packer support, means connected to the packer support and having a swiveling connection with the pipe support and including an expander, lower casing engaging means about said expander, releasable interengaging means between said means connected to said support and said casing engaging means, a yieldable seat forming a support for said casing en- 115 gaging means when the latter is released, interengaging means between the pipe support and the casing engaging means formed to permit their relative lengthwise movement and to prevent their relative rotation, a setting nipple above said packing ele- 120 ment and having an upper expander, casing engaging means about said upper expander, means connecting the setting nipple and packer support formed to permit their relative lengthwise movement and to prevent their relative rotation, a member having a threaded connection with said nipple and in- 125 terconnected with said last mentioned casing
- 130

engaging means and effective to actuate said last mentioned engaging means into position out of engagement with the casing, and means on said member limiting the longitudinal movement of said member, relative to the setting nipple.

8. A packer including a tubular packer support, an expansible packing element thereon, a tubular screen support below the 10 packer support, a tubular section connected to the packer support and having a swiveling connection with the screen support and including a downwardly tapering lower expander, casing engaging means about said 15 expander and having a releasable threaded connection with said tubular section, a yieldable seat supported on said screen support and whose upper end engages said casing engaging means, a setting nipple above said 20 packing element and having an upwardly tapering upper expander, casing engaging means about said upper expander, means having a threaded connection with said setting nipple said last mentioned means and said last mentioned casing engaging means having means which interengage and through which the latter may be actuated by the former out of casing engaging position.

In testimony whereof I have signed my 30 name to this specification.

GRANVILLE A. HUMASON.
